(57) **CLAIM**

The ornamental design for a smart camera, as shown and
described.

DESCRIPTION

FIG. 1 is a front, top, left side perspective view of a smart
camera showing my new design;

FIG. 2 is rear, bottom, right side perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a perspective view thereof in a first use state;

FIG. 10 is a perspective view thereof in a second use state;

FIG. 11 is a perspective view thereof in a third use state; and,

FIG. 12 is a perspective view thereof in a fourth use state.
The broken lines depict portions of the smart camera and
form no part of the claimed design.

1 Claim, 12 Drawing Sheets
